Fig. 3

FIG. 1 is a front elevational view of the combined fireplace grate and grill embodying my new design; FIG. 2 is an end elevational view thereof; and

FIG. 3 is a plan view thereof.

The present application is a divisional of my pending design patent application Ser. No. 7,138, filed on Mar. 13, 1967 for Fireplace Grate and Fireplace Grill, which latter application is further a continuation-in-part of my parent design patent application Ser. No. 3,423, filed on Aug. 11, 1966, for Fireplace Grate Design, presently abandoned.

I claim:

The ornamental design for a combined fireplace grate and grill, substantially as shown and described.
